Lacy Harry, Attorney,

UNITED STATES PATENT OFFICE.

HENRY F. HILDEBRANDT, OF SAN ANTONIO, TEXAS.

TUYÈRE.

Application filed February 24, 1922. Serial No. 538,986.

To all whom it may concern:

Be it known that I, HENRY F. HILDEBRANDT, a citizen of the United States, residing at San Antonio, in the county of Bexar and State of Texas, have invented certain new and useful Improvements in Tuyères, of which the following is a specification.

This invention relates to tuyères for blacksmiths' hearths and has for its object the provision of simple, inexpensive and efficient means whereby the quantity of air supplied to the fire may be regulated according to the needs of the work being done. Other incidental objects of the invention will appear in the course of the following description and the invention resides in certain novel features which are illustrated in the accompanying drawings and will be hereinafter fully set forth.

In the drawings—

Figure 1 is a perspective view of a tuyère embodying my improvements;

Fig. 2 is a central longitudinal section of the same;

Fig. 3 is a front elevation with parts in section;

Fig. 4 is a horizontal section through the air inlet nozzle.

In carrying out my invention, I employ a box or body 1 which is connected at its upper end in any convenient or preferred manner with the fire-box 2 and is provided with vertical partitions 3 dividing the interior of the box or body into a plurality of chambers leading directly into the fire-box. The lower end of the box or body is normally closed by a door 4 hinged at one edge to the back wall of the box, as shown most clearly in Fig. 2, and equipped at its free edge with a latch 5 consisting of a rock shaft journaled in suitable lugs or bearings 6 upon the door and having a sustaining finger 7 at its inner end adapted to engage over a projection 8 upon the box or body 1 so as to support the door against the bottom of the box and thereby close the same. The rock shaft 5 is extended beyond the end of the box or body and at its extended end is provided with a handle 9 of any preferred form whereby the latch may be easily manipulated. The walls of the fire-box are flared upwardly, as shown clearly in Figs. 1, 2 and 3, so that the air delivered to the fire may be allowed to spread and reach all parts of the fire so that combustion will be

promoted evenly throughout the same. To regulate and control the admission of air to the fire, I provide, at the juncture of the box or body 1 and the fire-box, valves 10 consisting of plates extending from end to end of the fire-box and carried by rock shafts 11 which are journaled in the end walls of the air box or body 1, handles 12 of any preferred form being provided upon one end of the rock shafts so that the valves may be readily set. As shown most clearly in Fig. 2, the inner or free edges of the valves approach closely to each other along the center of the fire-box, as shown at 13, so that, when the valves are in their lowered or closed position, a very thin stream of air will be admitted to the fire. Should it be desired, however, to admit a greater quantity of air to the fire, the valves are tilted upwardly, as indicated by dotted lines in Fig. 2, so that their inner opposed edges will be moved further apart, as will be readily understood.

In the front wall of the air box or body 1, I provide openings 14 which are so located that each opening will communicate with one of the chambers defined by the walls of the air box and the partitions 3, as clearly shown in Fig. 4, and upon the front wall of the box, I secure a forwardly projecting nozzle 15, the side walls of which converge forwardly, as clearly shown. Within the nozzle 15, I provide partitions 16 which diverge from the front end of the nozzle to the front wall of the air box and thereby define supplemental nozzles or passages each leading to one of the openings 14, as clearly shown. Guideways or cleats 17 are provided at the rear end of the nozzle and are secured to the front wall of the air box, and a sliding damper or cut-off plate 18 is mounted in the said guides and disposed between the front wall of the air box and the rear end of the nozzle. This damper or cut-off plate is provided with an opening 19 corresponding in size and form to the openings 14 and is further provided with a slot 20, the vertical dimensions of which is the same as the vertical dimension of the openings 14 and the horizontal dimension of which is such that the said slot may communicate with two of said openings. As shown in Fig. 4, the damper or cut-off plate 18 is set so that the central opening 14 is uncovered by reason of the slot 20 being disposed over the same, while the opening 19 in the damper is set

over an imperforate portion of the front wall of the air box and the end or outer openings 14 are covered by imperforate portions of the damper. It will be readily understood upon reference to Fig. 4 that, if the damper be slid to the right so that the slot 20 will uncover the opening 14 at the right, the central opening 14 will remain uncovered and, therefore, two of said openings 14 will be open to admit air through the air box to the fire. If, however, the damper be slid to the left so that the slot 20 will uncover the left-hand opening 14 without extending beyond said opening to the left, the said opening and the central opening 14 will be uncovered and the opening 19 will also be brought into register with the right-hand opening 14, so that all three of said openings will be uncovered.

20 The delivery spout of the blower is connected with the front or entrance end of the nozzle 15, as indicated by dotted lines in Figs. 1 and 2, and the air blast created by the blower will, therefore, be delivered into the said nozzle and will be divided into a plurality of streams by the partitions 16 and directed to the openings 14 to pass through the same into the air box and thence escape between the valves 10 to the fire. Some work performed by a blacksmith requires only a small volume of air to attain the desired results, while other work requires a greater quantity of air and other work requires a still greater quantity of air. By properly adjusting the slideable damper 18 and the valves or rocking dampers 10, the workman can nicely regulate the flow of air to the requirements of the particular work being done so that the desired results can be obtained without waste of fuel and without loss of time. My device is obviously simple and inexpensive in construction and may be ap-

plied to any blacksmith's hearth at a low cost. Cinders from the hearth will, of course, drop therefrom or may be raked therefrom through the space between the valves or dampers 10 and collected in the air box. When the accumulation of cinders is so great as to necessitate their removal, the latch 5 is released from its engagement with the projection 8, whereupon the weight of the door 4 and the cinders accumulated thereon will cause the said door to swing downwardly and discharge the cinders into any convenient receptacle placed below the tuyère. It will be readily noted that the construction and arrangement of the several elements of the device are such that a worn out part may be easily replaced without requiring the provision of an entirely new tuyère or the disassembling of all the members of the same.

Having thus described the invention, what is claimed as new is:

A tuyère comprising an air box having a plurality of chambers open at their upper ends and each provided in its front wall with an inlet opening, said inlet openings having the same form and area, a nozzle mounted upon the front wall of the air box and having a plurality of passages each leading to one of the said inlet openings, and a damper slidably mounted across the nozzle at the junction of the same with an air box and provided with an opening of the same form and area as the said inlet openings, a longitudinal slot having a length sufficient to extend over two inlet openings, and intervening imperforate portions whereby any one or more of the inlet openings may be covered or uncovered.

In testimony whereof I affix my signature.

HENRY E. HILDEBRANDT. [L.S.]
